BOOTH FOR A LOUNGE OR THE LIKE

Billy Joe Walters, 1916 "B" Demere Road,
Saint Simons Island, Ga. 31522

Filed May 26, 1969, Ser. No. 17,359

Term of patent 14 years

Int. Cl. 6—01

U.S. Cl. D80—2

FIG. 2

FIG. 1 is a side elevational view of a booth for a lounge or the like showing my new design; and

FIG. 2 is a perspective view thereof.

I claim:

The ornamental design for a booth for a lounge or the like, as shown.
